MEANS FOR ELECTRO-EROSION

Leslie Reginald Blake, Rugby, England, assignor to The British Thomson-Houston Company Limited, a British company

Application December 9, 1954, Serial No. 474,304

Claims priority, application Great Britain December 21, 1953

14 Claims. (Cl. 219—69)

This invention relates to apparatus for the working of material, particularly material of great hardness, by removing particles of it from the surface, utilising repeated electric discharges which act similar to the cutting effect of one or more sharp edges of a conventional tool. As compared with such conventional methods, "machining by electro-erosion" has many advantages. The tool electrode and its operating head are of light weight, and results can be achieved which are not possible with ordinary methods, for instance holes of irregular cross sectional shape, or with curved axes can be drilled, or complex patterns can be engraved with a suitably shaped tool electrode. Moreover, little or no mechanical or thermal stresses are set up by electro-erosion, and the work piece is left in a condition which is more strain-free than can be achieved with other methods.

The tool electrode can vibrate or rotate and may perform machining operations which are equivalent to drilling, milling, grinding, sawing and other conventional machining.

With conventional apparatus of this kind energy from a supply source is stored in a capacitor which is discharged in short pulses, the charging and discharging cycles being repeated at frequent intervals. It has also been known to connect a charging resistor between the condenser and the supply.

However the considerable loss of power in such a resistor can be avoided and the charging time can be reduced if an inductance device is included in the charging circuit, instead of or in addition to a resistor.

The present invention aims at an improved apparatus of this kind which is particularly suitable to be employed for high power output and machining rates. The invention also makes it possible to use simple control means, and affords a high charging efficiency.

Generally this invention resides in apparatus for machining by repeated electric discharges between tool and work piece electrodes, comprising a capacitance device connected between the tool and work piece, an inductance device through which the capacitance device is charged from a source of electric power to supply the discharges, a vibrator for varying over a given range and in repeated succession the distance between the tool and work piece, the range including the distance at which the discharges occur at a predetermined voltage of the capacitance device as required, the charging circuit and the vibrator being synchronised to ensure coincidence of said voltage and distance, a means for feeding to the discharge gap a scavenging fluid for removing the particles eroded from the electrodes, and an automatic progressing means which is controlled independently of the voltage across the discharge gap to produce an automatic progressive motion reducing the distance between the tool and work piece, thereby to maintain substantially constant the mean length of the discharge path, while particles are eroded and removed from the electrode surfaces.

As will be seen such apparatus can be supplied from direct current or alternating current sources, the removal

2

of the eroded particles is greatly facilitated, and the self-feed mechanism can be of great ruggedness.

More details and advantages of the invention will become apparent from the following description referring to the accompanying drawings, in which:

- 5 Fig. 1 is a schematic representation of apparatus of conventional design using a resistance charging circuit for the capacitor and electronic control for the automatic progressing means;
- 10 Fig. 2 is a diagram of the capacitor voltage obtaining with such an arrangement;
- 15 Fig. 3 shows diagrammatically a form of apparatus according to the invention;
- 20 Fig. 4 shows another embodiment;
- 25 Fig. 5 shows the voltage graph of the capacitance device;
- 30 Figs. 6 and 7 show embodiments substantially similar to Fig. 3, and adapted for supply from an alternating current source;
- 35 Fig. 8 shows capacitance voltage and current curves obtaining in the resonant circuit when no discharge occurs, and
- 40 Fig. 9 shows the shape of these curves when discharges occur in the apparatus of Figs. 6 and 7; and
- 45 Fig. 10 shows a variation of the combined vibrator and induction device.
- 50 With conventional apparatus as shown diagrammatically in Fig. 1 repeated electric discharges of extremely short duration and high intensity which produce the electro-erosion effect between the electrode or tool 1 and work piece 2 are supplied by a capacitor 3, arranged to be charged up via a resistor 4 from a direct current source. The work piece is connected to the positive side of the source and is usually earthed. The distance or gap between tool and work piece is so chosen that spark discharge occurs every time the charging capacitor 3 is charged up to a predetermined voltage. After the discharge of the capacitor the cycle of operation is repeated. A scavenging fluid which may be an electrolyte, but is preferably a dielectric material, such as a hydrocarbon, is fed to the discharge path so as to remove the eroded particles. The sparking distance between the electrodes—approximately 0.001 to 0.005 inch for discharge voltages of 30 to 200 volts—is maintained by an electronic servo mechanism 5 supplied through an amplifier 6 whose input is dependent upon the voltage across the discharge gap as compared with a reference voltage. The latter can be obtained from a potentiometer 8 having its ends 7 connected to a steady direct current source and its movable contact 9 connected to the work piece as shown. It will be understood that the sparking distance, discharge voltage and discharge repetition rate can be controlled by the setting of the reference voltage through the potentiometer.
- 55 While such an arrangement is satisfactory in many cases it has the disadvantage of necessitating an expensive and complicated, preferably an electronic equipment for controlling the progressive motion of the electrode 1. Furthermore the charging efficiency is poor since the capacitor voltage approaches asymptotically the value of
- 60 the supply voltage and a major portion of the power drawn from the source is dissipated in the charging resistor. Optimum cutting power is achieved at 36% efficiency when the discharge voltage V_d is 71% of the voltage V_s of the direct current source, but in practice
- 65 the efficiency can fall to less than 20%, which would mean that at a cutting output of 10 kilowatts the losses in the charging resistor may be as high as 40 kilowatts. A further disadvantage is that after the discharge a short-circuit path may exist between the electrode and work
- 70 piece for a period which is not negligible, causing delays in the charging operation, and non-uniformity in the peaks of the capacitor voltage at which discharge takes

place. These voltage and current conditions are diagrammatically shown by the V_s and V_c graphs of Fig. 2.

The above disadvantages are overcome by the apparatus of the invention which ensures high efficiency, ease of operation and constructional strength to withstand handling in a workshop, such apparatus including an inductance device in the charging circuit, a means for mechanically vibrating the electrode towards and away from the work piece, and a means which is controlled independently of the voltage across the discharge gap, for urging the electrode towards the workpiece and producing an automatic progressive motion which maintains substantially constant the mean length of the discharge gap while the eroded particles are moved from the surface of the electrodes by a scavenging fluid which is supplied under pressure through a tube 1a connected to a hollow tool electrode 1 so that the pressure fluid discharges into the spark gap at the open end 1b of the passage through the tool electrode.

As shown in Fig. 3 a capacitance device 3 which discharges across the gap between the electrode 1 and workpiece 2 is charged up from a direct current source through an inductance device 10', comprising the energising coil of an electromagnet 13 forming part of a mechanical vibrator which is provided for varying through a given range and in repeated succession the gap between 1 and 2. This range includes the distance at which discharges occur. The charging circuit now including inductance and capacitance has a natural resonance frequency

$$f_{ch} = \frac{1}{2\pi\sqrt{LC}}$$

The mechanical vibrations and the natural frequency of the vibrating system are related to this charging frequency, the frequency of the vibrations being preferably twice the charging frequency. Furthermore, the phase relation is such that the capacitance device is charged to a predetermined voltage when, due to the vibrating motion, the gap, which determines the discharge path, passes through a conditional value at which it will break down at the said predetermined voltage. The mechanical bias of the electrode tool towards the workpiece and the progressive feed of the electrode is obtained by gravity action using a suitable portion of the weight of a head carrying the tool and vibrating mechanism, the remaining portion of the weight being counterbalanced by a weight 12. Thus the progressive motion does not depend upon the voltage across the electrode gap and does not necessitate electronic control or servomotor means.

The operation is now as follows: Theoretically, as long as there is no discharge the voltage of the capacitor in the resonant inductance-capacitance circuit oscillates about the voltage V_s of the direct current supply source, the current, also of sinusoidal shape, attaining the value

$$V_s / \sqrt{LC}$$

For best operations discharge occurs at the first voltage maximum of the capacitance device, the value of which is now virtually twice the value of the supply voltage. The simplest way of triggering the discharge at this instant is to vibrate the electrode at twice the frequency of the charging circuit, and in such phase relation thereto that the electrode approaches the work piece to be at discharge or sparking distance when the capacitance device attains or is near its peak voltage. As the electrode vibrates it moves on to the work piece but the capacitance device is substantially discharged before the electrode contacts the work piece, and it rebounds immediately therefrom, its movement being similar to that of a pneumatic drill. The rapid rise of the capacitance voltage due to inductance charging, sudden discharge and immediate rebuilding of the capacitance voltage are indicated by the V_c in Fig. 5. During the discharge the current and field are concentrated to minute regions and cause erosion at

the surfaces of both electrodes as is known. If these surfaces are of similar material the erosion of the positive electrode is greater but the actual amount of erosion depends upon the kind of material. The eroded material is rapidly removed by a scavenging fluid preferably conducted to the discharge path through a hollow of the electrode 1 and out of the discharge end 1b, as previously explained. It is fed from the supply tube 1a under pressure which may be as high as 150 lbs. per square inch. 10 Various scavenging fluids have been tried with success and in our opinion a dielectric liquid, particularly a hydrocarbon, of the kind used for insulating and cooling transformers is very suitable. The scavenging fluid does not only prevent short circuiting of the capacitor by accumulation of eroded particles in the gap between the electrode and work piece but also causes de-ionization of the gap thus quenching the discharge so that the recharging of the capacitance device can follow. It will be understood that the de-ionization is enhanced as the electrode recedes from the work piece in the course of its vibration, and that this receding movement is accelerated by a rebounding action consequential to the electrode hitting the work piece. As a strong separating action is thus ensured automatic relative movement of the two electrodes with a view to maintaining a more or less constant gap between them in spite of the removal of eroded material from their ends can be readily accomplished by a simple biasing member controlling the automatic progressive means. In the embodiment of Fig. 3 20 the biasing is by gravity force, using a small portion of the weight of the tool head including the vibrator, the greater portion being counterbalanced by a weight 12.

A manual control (not shown in the drawings), of the tool head as is known in the art, can be provided to override the control by the automatic progressive means.

It will be understood that the capacitance value of 3, the frequency of the vibrator and the weight 12 which determines the biasing force can be made adjustable by simple means. It should also be noted that although 30 contact between the electrode and work piece must take place when the electrode hits the work piece the contact period is extremely short owing to the immediate rebounding effect. Furthermore it does practically not reduce the charging efficiency since at the beginning of the charging period the actual charging current is kept at a low value by the inductance device in the charging circuit.

Whilst any reciprocating mechanism whose movement is suitably related to the oscillations in the charging circuit could serve as the mechanical vibrator, a combined inductance device-electromagnetic vibrator unit which can readily be locked in phase with the charging circuit as shown in Fig. 3 is presently preferred. The tool 1 is carried by an armature 15 which is biased away from the magnet by a spring 14, preferably a leaf spring, which renders the construction compact and efficient.

The core 13 can have two legs each carrying a portion of the winding 10' as in Fig. 4, or, as shown in Fig. 10, a three-legged core 13a may be used which carries a single winding 10a on its centre leg.

The natural frequency f_{me} of the vibrating system now depends upon its mass and the stiffness of the spring. Obviously the attracting force varies with the magnetic force whose frequency f_{ma} is

$$\frac{1}{\pi\sqrt{LC}}$$

if the magnet coil forms part of a resonant circuit, such as the charging circuit of the capacitance device. For practical operation it has been found advantageous to make f_{me} greater than f_{ma} but satisfactory results can also be achieved with the charging frequency f_{ch} equal to or even slightly higher than the frequency of the vibration.

A switching means such as a current responsive circuit breaker or contactor 16 can be connected to interrupt at 70 17 the charging circuit if the period of contact between

the tool and work piece is continued, and undesirable short circuit conditions arise. Immediately after interruption the contactor recloses and momentary heavy current in coil 10a pulls the tool away from the work piece. Thus a short circuit is cleared within a few milliseconds, thereby to prevent undesirable fusion which would be liable to cause the tool electrode to adhere to the work piece and would interfere with the smooth operation of the tool which requires constant vibration. Power stored during this period in the charging inductance device is released thereafter to the capacitance device. For normal operation of the embodiment shown in Fig. 3 the V_c value follows the curve of Fig. 5.

Obviously the direct current embodiment as shown in Fig. 3 can be supplied from an alternating current source via a rectifier, and, since the efficiency of apparatus according to the invention is very high, the size of such a rectifier, and of a transformer if used in conjunction therewith, is small as compared with the equipment required for conventional apparatus.

However, the invention also enables the operation of electro-erosion apparatus from an alternating current supply source without the intermediary of a rectifier. The charging circuit of such apparatus, as shown in Fig. 6, for instance, including capacitance device 3 and inductance devices 10 and 10' is oscillatory and, as indicated in Fig. 8, the voltage V_c and current I_c of the capacitance device build up in oscillatory fashion until discharge occurs. The charging circuit is now tuned to the frequency of the supply so that the charging frequency substantially equals the supply frequency, and the vibrator can also be synchronised to this frequency. As the vibrator comprises an electromagnet supplied from the same supply system polarization using a permanent magnet or a rectifier shunting a coil energised by A. C. is suggested to ensure that discharge occurs at the second voltage peak of the capacitance device, and at the instant when the work piece is positive.

If A. C. is used the natural frequency of the mechanical system may equal substantially that of the magnetising current, that is the charging frequency, and need not be twice the frequency of the charging circuit as with direct current charging.

The embodiment of Fig. 7 employs alternating current charging with a combined inductance device-vibrator unit, similar to the one used in the embodiment of Fig. 3. As can be seen from the voltage and current graphs of Fig. 9, the discharge now occurs at the second voltage maximum of the device 3, and this can be ensured by the provision of a polarizing winding 18 energized with direct current, so that the total magnetic flux in the core 13 oscillates at the frequency of the charging circuit. In lieu of such a direct current winding a permanent magnet core can be used to achieve the desired polarization characteristic.

In Fig. 6 the winding 10' is connected in series with another induction coil 10 in the charging circuit to provide the total of the inductance required in that circuit, and the winding 10' is shunted by the rectifier 19 to afford a polarized characteristic of the electromagnetic vibrator. In the modification shown in this figure, the scavenging fluid is discharged under pressure into the spark gap through separate nozzle means 24 which includes a device, such as a reducing valve 25, for regulating the pressure of the scavenging fluid. This regulable supply of scavenging fluid under pressure which is thus provided affords a means for obtaining a finer adjustment of the gap between the tool electrode 1 and the work piece 2 as the force of the scavenging fluid in the gap upon these members tends to force them apart and can be regulated by the supply of scavenging fluid.

As is known a more economical capacitor of higher voltage and less microfarad value can be used if a transformer stepping down the voltage is arranged between the capacitance device 3 and the electrodes 1, 2 and an automatic switching means, which may be of the me-

chanical or electronic kind, can be arranged to disconnect the transformer during the charging periods of the capacitance device.

With apparatus according to the invention it has been possible to use cutting powers of up to 10 or 12 kilowatts, the cutting power being defined by the formula $\frac{1}{2}CV_d^2f$, wherein C is the capacitance of the device 3, V_d is the discharge voltage, and f is the discharge repetition frequency, to machine a work piece of tungsten carbide for instance at a rate of 0.5 cc. per minute, and to raise the efficiency of the charging operation to 95% as compared with a usual value of the order of 20% for electro-erosion apparatus with resistance charging.

While some practical embodiments have been illustrated and described it will be understood that constructional modifications and different circuit arrangements can be used without departing from the invention. For instance, a spring device or a stalling electric motor can supply or regulate the biasing force of the automatic progressing means. The latter embodiment is illustrated in Fig. 4 in which a stalling motor 20 with an adjustable torque, which can be adjusted by means of a potentiometer 21 independently of the voltage across the gap between the tool electrode and the work, exerts a force which biases the electrode 1 towards the work piece 2 through a suitable drive, such as a pinion 22 in engagement with a rack 23. In this arrangement, the scavenging fluid is discharged into the gap through nozzles 24 which may be mounted in any suitable manner independently of the electrode 1. An electromagnetic vibrator could have a moving coil instead of the usual soft iron armature.

When a transformer is arranged between a capacitance device charged from a direct current source and the discharge gap, mechanical or electronic switching means, as are known, should be provided for disconnecting the transformer during the charging periods.

What I claim is.

1. Apparatus for electrically eroding a workpiece of metal or metallic compound by means of rapidly repeated electric discharges between it and a tool electrode, comprising a source of electric power, a capacitor connected to said tool electrode and workpiece to supply the energy of each discharge, a charging circuit for recharging the capacitor from said source after each discharge, said charging circuit having a minimum of ohmic resistance so as to be practically non-resistive and purely inductive, at least a part of its inductance being provided by a coil which serves for energizing in synchronism with the charging cycles of the capacitor an electromagnetic vibrator, said vibrator connected to said tool electrode to decrease and increase the distance between the said electrode and workpiece, thus cyclically varying the resistance in the discharge gap to initiate a discharge of considerable energy therethrough at the end of each recharge of the capacitor, also comprising a first means for feeding a scavenging fluid under pressure to the discharge gap, thereby to remove particles disintegrated by the electric discharges, and a second means producing a biasing force urging the tool electrode towards the workpiece so as to prevent gap increase by the erosion of material or by the tendency of the pressure fluid to force the tool electrode and workpiece apart, said biasing force being substantially constant during operation and independent of the fluctuating tool electrode voltage.

2. Apparatus including a tool electrode for electrically eroding a workpiece of metal or metallic compound by means of rapidly repeated electric discharges between it and said tool electrode comprising a source of electric power, an electromagnetic vibrator for said tool electrode, a capacitor connected to said tool electrode and workpiece to supply the energy of each discharge, a charging circuit for recharging the capacitor from said source after each discharge, said charging circuit having a minimum of ohmic resistance so as to be practically non-resistive and purely inductive, a coil for energising said

electromagnetic vibrator in synchronism with the charging cycles of said capacitor and providing at least a part of the inductance of said charging circuit, said vibrator being connected to said tool electrode to decrease and increase the distance between the said electrode and workpiece and thereby cyclically varying the resistance in the discharge gap therebetween to initiate a discharge of considerable energy therethrough at the end of each recharge of said capacitor, means for feeding a scavenging fluid under pressure to the discharge gap for removing particles disintegrated by the electric discharges, and a means for producing and adjusting a biasing force urging said tool electrode towards the workpiece so as to prevent gap increase by the erosion of material or by the tendency of the pressure fluid to force said tool electrode and workpiece apart, said means for adjusting the biasing force being adjustable independently of fluctuations of the tool electrode voltage.

3. Apparatus for electrically eroding a workpiece of metal or metallic compound by means of rapidly repeated electric discharges between it and a tool electrode, comprising a source of electric power, a capacitor connected to said tool electrode and workpiece to supply the energy of each discharge, a charging circuit for recharging the capacitor from said source after each discharge, said charging circuit having a minimum of ohmic resistance so as to be practically non-resistive and purely inductive, at least a part of its inductance being provided by a coil which serves for energising in synchronism with the charging cycles of the capacitor an electromagnetic vibrator, said vibrator connected to said tool electrode to decrease and increase the distance between the said electrode and workpiece, thus cyclically varying the resistance in the discharge gap to initiate a discharge of considerable energy therethrough at the end of each recharge of the capacitor, also comprising a means for feeding a scavenging fluid under pressure to the discharge gap, thereby to remove particles disintegrated by the electric discharges, the tool electrode being carried on a tool head and a weight being provided to balance adjustably a portion of the gravity force of said head, thus to produce a biasing force urging the tool electrode towards the workpiece so as to prevent gap increase by the erosion of material or by the tendency of the pressure fluid to force the tool electrode and workpiece apart, said biasing force being substantially constant during operation and independent of the fluctuating tool electrode voltage.

4. Apparatus for electrically eroding a workpiece of metal or metallic compound by means of rapidly repeated electric discharges between it and a tool electrode, comprising an alternating current supply source, a capacitor connected to said tool electrode and workpiece to supply the energy of each discharge, a charging circuit for recharging the capacitor from said source after each discharge, said charging circuit having a minimum of ohmic resistance so as to be practically non-resistive and purely inductive, at least a part of its inductance being provided by a coil whose magnetic field is polarised by a unidirectional current conducting device connected in parallel thereto which coil serves for energising in synchronism with the charging cycles of the capacitor an electromagnetic vibrator, said vibrator connected to said tool electrode to decrease and increase the distance between the said electrode and workpiece, thus cyclically varying the resistance in the discharge gap to initiate a discharge of considerable energy therethrough at the end of each recharge of the capacitor, also comprising a first means for feeding a scavenging fluid under pressure to the discharge gap, thereby to remove particles disintegrated by the electric discharges, and a second means producing a biasing force urging the tool electrode towards the workpiece so as to prevent gap increase by the erosion of material or by the tendency of the pressure fluid to force the tool electrode and workpiece apart, said biasing force being

substantially constant during operation and independent of the fluctuating tool electrode voltage.

5. Apparatus for electrically eroding a workpiece of metal or metallic compound by means of electric sparks produced between it and a tool electrode, comprising a source of electric power, a capacitor connected to said tool electrode and workpiece to supply the energy for the sparking, a charging circuit for recharging the capacitor from said source after each discharge, said charging circuit having a minimum of ohmic resistance so as to be practically non-resistive and purely inductive, at least a part of its inductance being provided by a coil which serves for energising in synchronism with the charging cycles of the capacitor an electromagnetic vibrator, said vibrator being connected to said tool electrode to decrease and increase the distance between the said electrode and workpiece, thus cyclically varying the resistance in the discharge gap to initiate a spark discharge of considerable energy therethrough at the end of each recharge of the capacitor, and also comprising a first means for feeding a scavenging fluid under pressure to the discharge gap, thereby to remove particles disintegrated by the electric sparking, and a second means producing and adjusting a biasing force urging the tool electrode towards the workpiece so as to prevent gap increase by the erosion of material or by the tendency of the pressure fluid to force the tool electrode and workpiece apart, the adjustment of said biasing force being independent of fluctuations of the tool electrode voltage.
6. Apparatus including a tool electrode for electrically eroding a workpiece of metal or metallic compound by means of rapidly repeated electric spark discharges between the workpiece and said tool electrode comprising a direct current source, an electromagnetic vibrator for said tool electrode, a capacitor connected to said tool electrode and workpiece to supply the energy of each discharge, a resonant charging circuit for recharging said capacitor from said source after each discharge, said charging circuit having a minimum of ohmic resistance so as to be substantially non-resistive and purely inductive, means including a coil for energising said electromagnetic vibrator in synchronism with the charging cycles of said capacitor and providing at least a part of the inductance of said charging circuit, said vibrator being connected to said tool electrode to decrease and increase the distance between said electrode and workpiece at a frequency which approximates twice the frequency of said charging circuit and thereby cyclically varies the effective resistance in the spark discharge gap therebetween and initiates a spark discharge of considerable energy therethrough at the end of each recharge of said capacitor, means for feeding a scavenging fluid under pressure to the spark discharge gap for removing particles disintegrated by the electric spark discharges, and means for producing a biasing force on said tool electrode in such manner and of such magnitude that the tool electrode is advanced towards the workpiece for preventing undesirable gap increase by the erosion of material or by the tendency of the scavenging fluid to force said tool electrode and workpiece apart, said biasing force producing means being operable independently of and not responsive to fluctuations of the tool electrode voltage.
7. Apparatus for electrically eroding a workpiece of metal or metallic compound by means of rapidly repeated electric discharge sparks between it and a tool electrode, comprising an alternating current supply source, a capacitor connected to said tool electrode and workpiece to supply the energy of the discharge sparks, a charging circuit for recharging the capacitor from said source after each discharge, said charging circuit having a minimum of ohmic resistance so as to be practically non-resistive and purely inductive, at least a part of its inductance being provided by the magnet coil of an electromagnetic vibrator, operating in synchronism with the charging cycles of the capacitor, said vibrator being con-

nected to said tool electrode to decrease and increase at a frequency which equals approximately the frequency of the supply source, the distance between the said electrode and workpiece, thus cyclically varying the resistance in the spark gap to initiate a discharge of considerable energy therethrough at the end of each recharge of the capacitor, and also comprising a first means for feeding a pressure fluid to the discharge gap, for removing therefrom particles disintegrated by the electric discharges, and a biasing means for urging the tool electrode towards the workpiece so as to prevent gap increase by the erosion of material or by the tendency of the pressure fluid to force the tool electrode and workpiece apart, said biasing means operating substantially independent of the fluctuations of the tool electrode voltage.

8. Apparatus for electrically eroding a workpiece of metal or metallic compound by means of rapidly repeated electric discharges between it and a tool electrode, comprising a source of electric power, a capacitor connected to said tool electrode and workpiece to supply the energy of each discharge, a charging circuit for recharging the capacitor from said source after each discharge, said charging circuit having a minimum of ohmic resistance so as to be practically non-resistive and purely inductive, at least a part of its inductance being provided by a coil which serves for energizing in synchronism with the charging cycles of the capacitor an electromagnetic vibrator, said vibrator connected to said tool electrode to decrease and increase the distance between the said electrode and workpiece, thus cyclically varying the resistance in the discharge gap to initiate a discharge of considerable energy therethrough at the end of each recharge of the capacitor, and also comprising a means for feeding a scavenging fluid under pressure to the discharge gap, thereby to remove particles disintegrated by the electric discharges, and an electric motor mechanically interconnected with the tool electrode and constructed to supply a stalling torque which provides a biasing force urging the tool electrode towards the workpiece so as to prevent gap increase by the erosion of material or by the tendency of the pressure fluid to force the tool electrode and workpiece apart, said biasing force being substantially constant during operation and independent of the fluctuating tool electrode voltage.

9. Apparatus for electrically eroding a workpiece of metal or metallic compound by means of a plurality of electric discharges produced in rapid succession between it and a tool electrode, said apparatus including an electric supply, a capacitor connected to said tool electrode and workpiece to provide the energy of each discharge, a charging circuit for recharging the capacitor from said source after each discharge, the ohmic resistance of said charging circuit being kept at a minimum so as to render said circuit practically non-resistive and purely inductive, at least a part of its inductance being provided by the energizing coil of an electromagnetic vibrator vibrating in synchronism with the charging cycles of the capacitor, said vibrator being mechanically connected to said tool electrode to decrease and increase the distance between the said electrode and workpiece, whereby cyclical variation in the discharge gap conductivity causes a succession of discharges of considerable energy at the end of each recharge of the capacitor, and also comprising a means for forcing into the discharge gap a scavenging fluid suitable to remove particles disintegrated by the electric discharges, also including a spring means arranged to urge the tool electrode towards the workpiece so as to prevent gap increase by the erosion of material or by the tendency of said fluid to force the tool electrode and workpiece apart, said spring means functioning independently of the fluctuating tool electrode voltage.

10. Apparatus for electrically working metal or metallic compound using a rapid succession of electric spark discharges between it and a tool electrode, comprising an

electric supply, a capacitor connected to said tool electrode and workpiece to provide intensive discharges, a charging circuit for recharging the capacitor from said source after each discharge, said charging circuit being

- 5 practically non-resistive but purely inductive, including a coil which serves to energize in synchronism with the charging cycles of the capacitor an electromagnetic vibrator, said vibrator reciprocating said tool electrode to decrease and increase the distance between the said electrode and workpiece, for cyclically varying the resistance in the discharge gap to initiate intensive discharges therethrough at the end of each recharge of the capacitor, and also comprising a regulable supply of scavenging fluid under pressure to the discharge gap, suitable for removing 10 particles disintegrated by the electric discharges, and a biasing means for urging the tool electrode towards the workpiece so as to prevent gap increase by the erosion of material or by other tendency to force the tool electrode and workpiece apart, the operation of said biasing 15 means being substantially independent of the fluctuating tool electrode voltage.

- 20 11. Apparatus for electrically working metal or metallic compound by means of a plurality of successive electric discharges between it and a tool electrode, comprising a source of electric power, a capacitor connected to the said tool electrode and workpiece to supply the energy of each discharge, a charging circuit for recharging the capacitor from said source after each discharge, said charging circuit being practically non-resistive and purely 25 inductive, at least a part of its inductance being provided by a coil arranged to energize in synchronism with the charging cycles of the capacitor an electromagnetic vibrator, connected to said tool electrode to decrease and increase the distance between the said electrode and workpiece, thus cyclically varying the discharge gap resistance at the end of each recharge of the capacitor, a switch being provided in said capacitor charging circuit and controlled 30 to open automatically if the current exceeds a predetermined value which may cause undesirable fusion of material and obstruction to electrode withdrawal after the current is interrupted, a pressure fluid feed for scavenging the discharge gap and a biasing means for advancing the tool electrode towards the workpiece so as to prevent gap 35 increase by the erosion of material or other undesired tendency to force the tool electrode and workpiece apart, said biasing means operating independent of the fluctuating tool electrode voltage.

- 40 12. Apparatus for working metal or metallic compound by electric sparking between it and a tool electrode, comprising a source of electric power, a capacitor connected to it via said tool electrode, and to the workpiece to supply the spark energy, a charging circuit for the capacitor being selected to be practically non-resistive but inductive, and including the energizing coil of an electromagnetic vibrator arranged to operate in synchronism with the charging cycles of the capacitor cyclically to vary the resistance in the discharge gap by changing the distance between the said electrode and workpiece to thereby initiate high intensity spark discharges at the end of each recharge of the capacitor, the tool electrode carried by a leaf spring in such fashion that it depends therefrom at a center point thereof while the ends of said spring are fastened to the electromagnet of the vibrator, and also 45 means for directing a fluid under such pressure to the discharge gap that it scavenges therefrom undesired particles, and a biasing means urging the tool electrode towards the workpiece with a force as required to prevent gap increase by the erosion of material or other tendency, the operation of said means being independent of the fluctuating tool electrode voltage.

- 50 13. Apparatus as claimed in claim 7 wherein means including a permanent magnet core is provided to said vibrator for polarizing said vibrator to oscillate at the 55 frequency of the charging circuit.

14. Apparatus as claimed in claim 7, wherein the vibrator has a soft iron core polarized by an electric winding so as to oscillate at the frequency of the charging circuit.
